ADJUSTABLE HOSE DRIER

George T. Dale, Sea Cliff, N. Y.

Application May 16, 1946, Serial No. 670,203

7 Claims. (Cl. 223—77)

1

My invention relates to improvements in hose driers and more particularly to a hose drier that may be adjusted to accommodate a variety of sizes of hose.

An object of my invention is to provide an adjustable hose drier that will positively maintain the size for which it is set. Another object is to provide an adjustable drier that is simple to operate and in which the mechanism for adjusting the drier to a desired size will not interfere with placing the hose on or removing the hose from the drier. Other objects and advantages of my invention will be apparent from the following description and the accompanying drawings, in which:

Fig. 1 is a front view of a drier embodying my invention;

Fig. 2 is an enlarged view of a portion of the drier illustrated in Fig. 1 and including the adjustable portion;

Fig. 3 is a section view taken along the line 3—3 of Fig. 2;

Fig. 4 corresponds to Fig. 3 and shows the fastening device illustrated in Fig. 3 in unclasped position, the other portions of Fig. 3 being omitted;

Fig. 5 is a section view taken along the line 5—5 of Fig. 2; and

Fig. 6 is a section view taken along the line 6—6 of Fig. 3.

Referring to the drawings in detail, there is a frame 10 conforming generally to the size and shape of a given type of hose; for example, a man's sock. The frame 10 is preferably made of wire which is bent to the desired shape. The wire is of sufficient size so that the frame will not collapse. The wire may be of stainless steel or other metal that will not corrode or rust or it may be treated or plated to resist corrosion and rusting.

The frame may be provided with a centrally located strut or brace 11 that extends parallel to the sides of the frame from the toe to the upper portion thereof. A heel portion 12 is slidably mounted on the frame 10 and has a pair of guide arms 13 and 14 that extend to the central brace 11 and engage slidably therewith. The heel portion may be formed of wire similar to the frame. The wire forming the heel may be looped about the frame and the central strut in a manner that will permit sliding movement of the heel portion 12 relative to the frame 10 and the central brace 11. Thus, the heel portion 12 may be moved along the frame 10 to the proper position for the size of hose to be dried. To facilitate this adjustment, size markings may be provided on the frame 10. In

2

the illustrated embodiment, the size markings on the frame are arranged to be used as a setting for the upper guide arm 14 of the heel portion to secure the desired size.

5 The guide arm 14 also carries a locking device which prevents movement of the heel portion after it has been positioned at the desired size. The locking device consists of a coiled member 15 formed from a wire 15 of spring steel. The coils 10 of the wire 15 are wrapt around the central brace 11, and the ends of the wire 15 extend from the coil. One end of the wire is held to the guide arm 14 by being looped around the arm and by a band 16. The other end of the wire 15 is free, and has 15 a hooked end 17 that may be latched over the guide arm 14. This end of the wire 15 is also bent to provide a trigger 18 for operating the latching mechanism. The trigger 18 is formed so that it lies in the same plane as the frame of the drier and when it is in locked position, the hose will 20 pass over the entire mechanism without interference.

The coiled portion of the wire 15 which is wrapt around the central brace 11 is arranged so that 25 when the hooked end 17 of the wire 15 is latched over the guide arm 14, the coils are drawn into firm engagement with the central brace 11, thus preventing movement of the heel portion relative to the frame. This holds the heel portion 12 positively at the desired size so that it will resist any force tending to move it such as may be exerted by the hose in drying. Woolen hose, for example, may exert considerable force in this respect, and any movement of the heel under such circumstances would make the drier ineffective for the important function of sizing the hose.

When the latch 17 is released, the coils of the wire 15 around the central brace 11 are permitted to expand circumferentially so that they will slide 40 along the brace 11 so as not to interfere with movement of the heel portion 12 to the desired size.

While a preferred embodiment of my invention has been described and illustrated herein, it will 45 be obvious to those skilled in the art that various modifications and changes may be made without departing from the scope of the invention as defined by the appended claims.

I claim:

50 1. In a hose drier of the class described, a frame conforming generally in shape and size to a given type of hose, a central brace located between the outer members of said frame, a heel portion slidably mounted on the frame, said heel portion having a pair of arms extending to and

slidably engaging with said central brace and a locking device carried by one of said arms and engaging with said central brace for securing said heel portion positively at a predetermined position on said frame.

2. A hose drier of the class described comprising a frame conforming generally in size and shape to a given type of hose, a brace located between the outer members of said frame, an adjustable heel portion slidably mounted on said frame, a guide arm carried by said heel portion and slidably engaging with said brace, and a locking device carried by said guide arm and engaging with said brace to lock said heel portion in place at a predetermined position on said frame.

3. In a hose drier as set forth in claim 2, a locking device consisting of a resilient coiled member carried by said guide arm and surrounding brace, said coiled member having one end secured to the guide arm and its other end movable to bring said coiled member into gripping engagement with said brace, said movable end being engageable with a rigid member of the drier to maintain said coiled member in said gripping position.

4. A hose drier of the class described comprising a frame, an adjustable heel portion slidably mounted on said frame, a guide arm carried by said heel portion and extending at least partially across said frame, said guide arm slidably engaging with an oppositely disposed portion of said frame, a resilient coiled member carried by said guide arm and surrounding a portion of said frame, one end of said coiled member being secured to said heel portion and its other end being movable to bring said coiled member into gripping engagement with said frame, and a latch on said movable end engaging with said guide arm to maintain said coiled member in gripping engagement with said frame and thereby lock said heel portion in a predetermined position on said frame.

5. A hose drier of the class described comprising a frame, an adjustable heel portion slidably mounted on said frame, a guide arm carried by said heel portion and extending at least partially across said frame, said guide arm slidably

engaging with an oppositely disposed portion of said frame, a resilient coiled member carried by said guide arm and surrounding a portion of said frame, one end of said coiled member being secured to said heel portion and its other end being movable to bring said coiled member into gripping engagement with said frame, said movable end being engageable with a rigid member of the drier to maintain said coiled member in gripping position.

6. In a hose drier of the class described having a frame and an adjustable heel portion slidably mounted on said frame, a locking device for securing said heel portion in a predetermined position on said frame comprising a resilient coiled member carried by said heel portion and surrounding a portion of said frame, said coiled member having one end secured to said heel portion and its other end being movable to bring said coiled member into gripping engagement with said frame, and a latch carried by said movable end engageable with said heel portion to maintain said coiled member in gripping engagement with said frame.

7. In a hose drier of the class described having a frame and an adjustable heel portion slidably mounted on said frame, a locking device for securing said heel portion in a predetermined position on said frame comprising a resilient coiled member carried by said heel portion and surrounding a portion of said frame, said coiled member having one end secured to said heel portion and its other end being movable to bring said coiled member into gripping engagement with said frame, said movable end being engageable with a rigid member of the drier to secure said coil in gripping engagement with said frame.
